UNITED STATES PATENT OFFICE.

HARRY R. MAXON, OF MUNCIE, INDIANA, ASSIGNOR TO MAXON BROTHERS COMPANY, OF CHICAGO, ILLINOIS, A CORPORATION OF DELAWARE.

APPARATUS FOR COMBUSTION OF GAS.

1,262,078.

Specification of Letters Patent. Patented Apr. 9, 1918.

Application filed October 9, 1916. Serial No. 124,747.

To all whom it may concern:

Be it known that I, HARRY R. MAXON, a citizen of the United States, residing at Muncie, in the county of Delaware and State of Indiana, have invented certain new and useful Improvements in an Apparatus for Combustion of Gas; of which the following is a specification.

My invention relates to means for securing a complete mixture of the combustible gas with air and complete combustion of the mixture beginning immediately as it enters the combustion chamber from the burner in a so-called lazy flame, to wit, one in which the gases travel but slowly. For this purpose I employ a fan or its equivalent which receives the air to support combustion at substantially atmospheric pressure and preferably, where no preheating is employed, directly from the atmosphere. The fuel gas, previously unmixed with air, is also fed into the fan casing, in which the air and gas are mixed in suitable proportions to support combustion, the percentage of air being somewhat in excess of that theoretically required. The mixture is fed to the furnace through a conduit of considerable capacity and unobstructed throughout whereby the inflammable mixture reaches the burner or opening into the combustion chamber in great volume at low pressure, and is immediately ignited and consumed in a lazy flame.

In the accompanying drawings I have shown a preferred embodiment of the invention and in the following specification described the same specifically. It is to be understood, however, that the specific disclosure is for the purpose of exemplification only and that the scope of the invention is defined in the following claims in which I have endeavored to distinguish it from the prior art without, however, relinquishing or abandoning any portion or feature thereof.

In the drawings, Figure 1 is a front elevation of a furnace having my invention applied thereto; and Figs. 2 and 3 side and front elevations respectively of the pump which is employed in carrying out my invention, Fig. 2 being partly in section to better show the construction.

I have shown my invention in Fig. 1 as applied to a group of ordinary heating furnaces 4 though it will be obvious that it may be used in connection with any other

device where a high degree of heat is desirable. Each furnace may be provided with one or more burners and in the present instance I have shown two burners 5, 5, for each furnace and each burner is connected to a separate fan 6, 6, by a pipe 7, 7 for supplying it with the proper mixture of gas and air. The burner preferably is so connected to the furnace that there is no substantial excess of air about the same though in its broader aspect my invention may be utilized where more or less air, in addition to that supplied by the fan, is introduced adjacent the burner. The fan casing 8 and fan proper 9 may be of any usual or approved type but preferably the air inlet to the casing is provided with a rotary valve or damper 10 which may be adjusted to control the supply of air to the fan. An inlet pipe 11 for supplying gas to the fan is mounted concentrically of the air inlet and damper and in the construction shown forms the arbor for the latter. The gas inlet pipe 11 is provided with a valve 12 for controlling the supply of gas.

By means of the valve and damper the relative quantities of air and gas admitted to the fan may be regulated and in practice they are so set as to furnish the proportions of air and gas found to furnish the most satisfactory combustion, the proportion of air being somewhat in excess of that theoretically required to support combustion. The air and gas entering the fan are very thoroughly mixed therein and driven forward to the burners at a speed sufficient to overcome the tendency of the flame at the burner to strike back or travel toward the fan. Thus by driving the combustible mixture to the burner at sufficient speed striking back is prevented without the use of screens, etc., commonly employed for this purpose, the proper speed and mixture being obtained by adjusting the damper and valve and speed of revolution of the fan. Even in the event of an improper mixture or speed the combustion or explosion is limited to the fan chamber in which the mixture is first made. My improved apparatus makes it feasible to make each furnace of a bank and each burner of the furnace absolutely independent of the other furnaces and burners so that in the event that it is necessary to put one of the burners or furnaces out of operation, as for example, for making repairs, 110

the operation of the other furnaces and burners is not interfered with.

I claim:

1. An apparatus for burning gas comprising a fan having a central opening, a fuel supply pipe connected to said opening, and a damper surrounding the fuel supply pipe and controlling the admission of air.
2. An apparatus for burning fuel comprising a fan having a central opening, a fuel supply pipe connected to said opening but of smaller diameter leaving an air-supply opening adjacent the same, and a rotary valve mounted on the fuel-supply pipe and adapted to close the air opening.
3. In a device of the class described, a burner, a fan, an unobstructed conduit leading from the fan to the burner, the casing

of the fan being directly open to the atmosphere to admit air to the fan at atmospheric pressure, a valve for regulating the quantity of air admitted to the casing, a pipe for supplying fuel gas directly to the casing, a valve for controlling the supply of gas, and means outside the casing for driving the fan.

4. In a device of the class described, a burner, a fan adapted and arranged to receive air at substantially atmospheric pressure, an unobstructed conduit leading from the fan to the burner, a valve for regulating the quantity of air admitted to the casing, a pipe for supplying fuel gas directly to the fan casing, a valve for controlling the supply of gas, and means outside the casing for driving the fan.

HARRY R. MAXON.
